UNITED STATES PATENT OFFICE.

ALEXANDER ZEBROWSKI, OF STAMFORD, CONNECTICUT.

SHADE-BRACKET.

1,353,695.

Specification of Letters Patent. Patented Sept. 21, 1920.

Application filed May 14, 1920. Serial No. 381,277.

To all whom it may concern:

Be it known that I, ALEXANDER ZEBROWSKI, a citizen of the Republic of Poland, residing at Stamford, in the county of Fairfield and State of Connecticut, have invented 5 certain new and useful Improvements in Shade-Brackets, of which the following is a specification.

My invention relates to shade brackets 10 and has for its purpose to provide an improved construction of bracket of this type in which the shade hanger can be adjusted to conform with different sizes of shades and thus eliminate the necessity of changing 15 the fixture each time a slightly different size shade is put up and thereby leaving an unsightly disfigurement of the window frame.

I will describe my invention in the best form known to me at present, but it will be 20 understood that the same is susceptible to changes in forms and proportions and to desirable mechanical additions with the exercise of only ordinary mechanical skill and without departing from the scope of the 25 appended claims.

In describing my invention in detail reference will be had to the accompanying drawing wherein like characters of reference denote corresponding parts in the several 30 views, and in which—

Figure 1 is a view in elevation of my improved shade bracket applied to a window frame;

Fig. 2, a section on the line 2—2 of Fig. 1; 35 Fig. 3, a rear view of the front plate of the bracket;

Fig. 4, a section on the line 4—4 of Fig. 3;

Fig. 5, a section on the line 5—5 of Fig. 1; and 40 Fig. 6, a perspective view of the adjustable hanger.

Referring to the drawings my improved shade bracket is shown as comprising a front plate A provided with a central opening 10. 45 On the inner face of the front plate A at each end thereof I provide spacing bosses 11 and 12 which form a seat for a back plate B. The front plate A is provided adjacent each end with securing screw passages 13 and 14 which are adapted to register with corresponding passages 15 and 16 in the back plate B respectively. Such securing screws as shown at 17 in Fig. 1 and when 50 the bracket is applied these screws serve not only to secure the bracket to the window frame as a whole, but they also serve to

clamp the front and back plates together for a purpose that will presently appear. The upper and lower edges of the front plate A are provided respectively with inwardly directed flanges 18 and 19 and the back plate B seats between these flanges. Formed in the rear face of the front plate A above the opening 10 parallel to the short axis of the plate is a series of notches 20, 60 65 while a corresponding series of notches 21 is provided below the opening 10.

The shade hanger element of the bracket is indicated at C and comprises a forwardly projecting main portion 22 which extends 70 through the opening 10. At the inner end of the portion 22 the hanger is turned laterally at substantially right angles to form an anchoring portion 23, which extends between the upper and lower portions of the plate A 75 and the corresponding portions of the plate B. This anchoring portion 23 of the hanger C is provided with forwardly directed extensions 24 and 25 for co-operation respectively with the notches 20 and 21. 80

From the foregoing construction it will be obvious that when the screws 17 are initially applied to secure the bracket in place the plates A and B can be separated to permit disengagement of the extensions 24 and 25 85 from the notches 20 and 21 respectively and as a result the hanger C can be adjusted in the opening 10 to suit the size of the shade being hung. This adjustment will bring the extensions 24 and 25 in registry with certain 90 of the notches 20 and 21 when the screws 17 are operated home to clamp the plates A and B together and thereby positively force the extensions 24 and 25 into certain of the notches 20 and 21 respectively, with the result that the hanger is thereby locked against 95 movement relative to the plates A and B.

It will be observed that the range of the adjustment of the hanger C is quite extensive and that such adjustment can be accomplished without removing the bracket as a whole from the window frame. It will also be observed that the parts of the bracket are relatively simple in construction and that all of them can be easily and cheaply manufactured by casting or by stamping, which will render the resulting article very cheap of 100 105 production.

I claim:

1. An adjustable shade bracket comprising a front plate having a central opening and provided on its inner side above and

2
below the opening with corresponding grooves parallel to the short axis of the plate, spacing bosses on the inner side of the front plate at each end thereof, a back plate seated on said bosses, means for clamping said plates together, a shade hanger projecting through the opening in the front plate and having a rear portion disposed between said plates and provided with means engageable in corresponding grooves above and below the opening when the plates are clamped together to secure said hanger in a desired adjusted position with respect to the plates.

10 2. An adjustable shade bracket comprising front and rear plates, the former being provided with grooves in its rear face and a

central opening, means for clamping the plates together, and a shade hanger projecting through said opening and having a rear portion disposed between the plates provided with means engageable in a groove in the rear face of the front plate when said plates are clamped together to secure the hanger in an adjusted position with respect to said plates. 20 25

In testimony whereof I hereunto affix my signature in the presence of two witnesses.

ALEXANDER ZEBROWSKI.

Witnesses:

FRANK E. JAMROZY,
MAY FREY.
